UNITED STATES PATENT OFFICE.

AUGUST D. COOK, OF LAWRENCEBURG, INDIANA.

TUBE-WELL.

SPECIFICATION forming part of Letters Patent No. 654,875, dated July 31, 1900.

Application filed November 25, 1898. Serial No. 697,403. (No model.)

To all whom it may concern:

Be it known that I, AUGUST D. COOK, a citizen of the United States, residing at Lawrenceburg, in the county of Dearborn and State of Indiana, have invented certain new and useful Improvements in Tube-Well; and I do hereby declare the following to be a full, clear, and exact description of the invention, such as will enable others skilled in the art to which it appertains to make and use the same.

My invention relates to well accessories; and the objects in view are to produce for application within the well-tube a cheap, strong, and readily applied and adjusted support for sustaining in a stable manner any of the working parts of the pump—such, for instance, as a working barrel, a foot-valve, an inner pump-pipe, or, in fact, anything that it may be desired to support in a well at a point distant above the strainer or above the bottom of the well, where no strainer is used. Heretofore in this class of wells difficulty has been experienced in providing an efficient or solid foundation for such parts of a well as the working barrel, foot-valve, inner pump-pipe, &c., or where any part was placed above the lower end of the pipe or well-tube in that the same was subject to slipping or becoming forced downward farther into the well-tube than was desired. By my invention, however, I avoid these objections, all as will hereinafter appear in the following detail description; and my invention consists in certain features of construction hereinafter particularly described, and specifically pointed out in the appended claim.

Referring to the drawings, Figure 1 is a sectional view of the lower portion of the well-tube or that portion in which my invention is located, the invention being shown as applied. Fig. 2 is a detail showing my invention. Fig. 3 is a detail of a modified form of my invention.

Like numerals of reference indicate similar parts in the figures of the drawings.

1 designates the usual cylindrical pipe or well-tube; 2, the support or anchor which constitutes my invention, and 3 the tapered tube employed in connection with my support or anchor in a manner hereinafter described, all as shown assembled in Fig. 1 of the drawings.

In practicing my invention I prefer to construct the support or anchor from a tube, of brass, the same being of such diameter as to adapt it to readily slip within the well tube or pipe. Within the lower end of this tubular support or anchor I may locate a ring or annulus 4, which is provided with an annular flange or shoulder arranged to receive the wall of the support or anchor, to which it is secured by riveting or in any other suitable manner. When in position, said ring constitutes a "hold," by which the device as a whole can be raised or lowered, a suitable tool being employed for this purpose. From its upper end to a point about midway its length the wall of the support or anchor is at intervals provided with longitudinal kerfs or slits 5, the intermediate portions of the metal constituting spring-tongues 6, which may be, and preferably are, slightly spread or deflected before the support or anchor is inserted into the well-tube. These spring-tongues may be formed or provided with any desired means for causing their upper free ends to engage, frictionally or otherwise, with the inner surface of the pipe or well-tube; but I prefer to rivet the upper end of each of the said spring-tongues to the reduced shouldered portion of a segmental jaw 7, the presence of which slightly increases the diameter of the anchor or support. These jaws 7 may have their outer surfaces roughened or serrated, as at 8, to enable them as a whole to be forced or driven into supporting engagement with the inner surface of the well-tube, in a manner hereinafter described.

As shown in the modification illustrated in Fig. 3, I may employ a metal ring 9, the same forming a hold, as previously described, and in addition constituting a circular frame or former in that the spring-tongues 10 are in this instance independently formed and consist merely of spring-strips riveted or otherwise secured at their lower ends to the ring. Other modifications of the support or anchor will readily suggest themselves, and for this reason I would have it understood that I do not limit my invention to the precise details of construction herein laid down, but hold that I may vary the same in any manner and to any extent within the knowledge of the skilled mechanic.

In operation the support or anchor is at first slightly spread at its upper end, so that it is of greater diameter at that end than the pipe or well-tube, after which it is forced down into the said well-tube, the previous or preliminary spreading of the spring-tongues being sufficient to cause the anchor to take a firm hold on the inner surface of the well-tube. This having been done, the tapered tube 3 is lowered into the upper end of the support or anchor and being forced down into the same caused the teeth of the jaws to firmly engage the inner surface of the well-tube and maintain said teeth in said engagement, so that the anchor is firmly set and cannot be farther driven down except by a removal of the tapered tube. If the tapered tube is of sufficiently-light metal to entail or result in any yield, it will conform to the shape of the well-tube and compensate for any irregularities in the same.

I am aware that numerous devices have heretofore been employed in connection with the exteriors of various kinds of well-pipes for the purpose of aiding in the expansion of certain elastic packings at desired points thereon. Such devices, however, have nothing in common with my invention, as I have

no such object in view as the expansion of a packer, either within or without a well-pipe where a joint is formed, but to produce an anchor or support wholly within the well-pipe capable of sustaining the weight of any part of the pump mechanism, as I have heretofore pointed out. In other words, by the terms "anchor" or "support" as I have employed them in the specification I mean merely a seat.

Having described my invention, what I claim is—

The combination with a well-tube, of a tubular anchor comprising a cylindrical body having its upper end flared and provided with kerfs or slits forming spring-tongues, a ring having an annular flange or shoulder arranged to receive the lower end of said body, serrated jaws secured to said tongues and having reduced flanged portions arranged to receive the latter, and a conical spreader arranged to spread said tongues.

In testimony whereof I affix my signature in the presence of two witnesses.

AUGUST D. COOK.
